UNITED STATES PATENT OFFICE.

ROBERT KUHN, OF DETROIT, MICHIGAN.

SOLDERING-IRON.

1,214,186.

Specification of Letters Patent. Patented Jan. 30, 1917.

Application filed September 4, 1915. Serial No. 48,968.

To all whom it may concern:

Be it known that I, ROBERT KUHN, a citizen of the United States of America, residing at Detroit, in the county of Wayne and State of Michigan, have invented certain new and useful Improvements in Soldering-Irons, of which the following is a specification, reference being had therein to the accompanying drawings.

- 10 The invention relates to electrically heated tools, being more particularly designed for use in electrically heated soldering irons, and the invention comprises the novel construction as hereinafter set forth.
- 15 In the drawing: Figure 1 is a sectional elevation of the casing; Fig. 2 is an elevation of the heating unit insertible in said casing; Fig. 3 is an enlarged section of the securing joint between the heating unit and casing; Fig. 4 is a section on line α — α of Fig. 3; and Fig. 5 is an elevation of the completed instrument.

20 A is the heating element, which is in the form of a centrally recessed body surrounded by the heating resistor.

25 B is the tool insertible in the recess in said body, and locked in position by suitable means such as the dog C.

30 D are electric terminals extending from the resistor E, which surrounds the body A, oppositely from the tool B.

To incase the instrument and also to form a handle connection therefor, I have provided a casing F, preferably formed of drawn tubing, and having a cylindrical portion G for receiving the member A. Adjacent to this cylindrical portion is a reduced portion H, which is cut away at I, preferably upon opposite sides thereof. Ad- 35 jacent to the portion H is a shank portion J, which at its end is provided with a threaded member K for engagement with a hollow handle L. The member K is also adapted for attachment to an insulator block M upon which the electrical terminals are mounted and attached to the flexible conductor cord N.

To secure the member A within the portion G of the casing, said member is provided at its inner end with segments O externally threaded and of a diameter slightly in excess of the diameter of the portion H.

These segments are adapted to fit in the cut-away portions I of the member F with the threaded portion projecting outward as shown in Figs. 3 and 4. The ring nut P is then engaged with the threads of the segments O and secured against the shoulder of the casing. This will securely hold the member A from displacement while the ring B will conceal the cut-away portions of the casing. The terminals D pass through the hollow shank of the casing to the insulator terminal block M, and the hollow handle L is then secured by means forming no part of the present invention.

What I claim as my invention is:—

1. The combination with a cylindrical heating unit and terminals extending from one end thereof, of a casing for said unit formed of continuous tubing having a cylindrical portion for receiving said unit and a reduced shank portion for receiving the terminals and for connection with the handle.

2. The combination with a cylindrical heating unit and terminals extending from one end thereof, of a casing for said unit comprising continuous tubing having a cylindrical portion and a reduced portion partly cut away, a threaded segment upon said unit engaging said cut-away portion, and an internally threaded ring surrounding said reduced portion and engaging said threaded segment.

3. The combination with a cylindrical heating unit and terminals projecting from one end thereof, of a casing for said unit comprising tubing having a cylindrical portion, a reduced portion partly cut-away with a shoulder therebetween against which one end of said unit is adapted to bear, a threaded segment on said unit for engaging said cut-away portion, and an internally threaded ring surrounding said reduced portion, engaging said segment and clamping said unit against said shoulder.

4. In an electrically heated instrument, the combination with a cylindrical heating unit having terminals extending from one end thereof, of a casing for said unit formed of tubing having a cylindrical portion for receiving the unit, a reduced shank portion for receiving the terminals and an interme-

diate portion partially cut away and forming a shoulder between the same and said cylindrical portion, a threaded segment on said heating unit engaging said cut-away portion, and an internally threaded ring surrounding said intermediate portion and engaging said threaded segment.

In testimony whereof I affix my signature in presence of two witnesses.

ROBERT KUHN.
